United States Patent

Des. 240,446
Patented July 6, 1976

240,446

COIN BANK

Tony Robert, 5701 Southwest Freeway,
Houston, Tex. 77057

Filed Feb. 21, 1975, Ser. No. 551,531

Term of patent 14 years

Int. Cl. D31—00

U.S. Cl. D34—11 R

FIG. 1 is a front perspective view of a coin bank showing my new design;

FIG. 2 is a front elevational view thereof;
FIG. 3 is a right side elevational view thereof; and

FIG. 4 is a top plan view thereof.

I claim:

The ornamental design for a coin bank, as shown and described.
